Des. 240,051
Patented May 25, 1976

240,051

FARROWING HOUSE

Mary K. Mayfield, 6707 W. 80th St.,
Overland Park, Kans. 66204

Filed June 28, 1974, Ser. No. 484,655

Term of patent 14 years

Int. Cl. D30—02

U.S. Cl. D30—1

Fig. 1.

Fig. 2.

Fig. 3.

Fig. 4.

Fig. 5.

Fig. 6.

FIG. 1 is a perspective view of a farrowing house, showing my new design;

FIG. 2 is a right side elevational view.

FIG. 3 is a left elevational side view;

FIG. 4 is a rear elevational view;

FIG. 5 is a plan view, and

FIG. 6 is a perspective view of a modified form of the farrowing house.

I claim:

The ornamental design for a farrowing house, substantially as shown and described.
